US0D1106198S

(12) **United States Design Patent** (10) **Patent No.:** **US D1,106,198 S**
(45) **Date of Patent:** **** Dec. 16, 2025**

(54) **WIRELESS MONITORING RECEIVER**

(71) Applicant: **Enping OLSK Electronic Co., Ltd.,**
Guangdong (CN)

(72) Inventor: **Xiaorong Huang**, Guangdong (CN)

(**) Term: **15 Years**

(21) Appl. No.: **29/991,066**

(22) Filed: **Feb. 26, 2025**

(51) **LOC (15) Cl.** **14-02**

(52) **U.S. Cl.**

USPC **D14/358**; D14/217; D14/218

CLAIM

The ornamental design for a wireless monitoring receiver, as shown and described.

DESCRIPTION

FIG. 1 is a front, top and right-side perspective view of the wireless monitoring receiver showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom and left-side perspective view thereof.

The broken lines throughout the drawing figures depict portions of the wireless monitoring receiver that form no part of the claimed design.

1 Claim, 8 Drawing Sheets
